UNITED STATES PATENT OFFICE.

WILLIAM HODGSON, OF NEW YORK, N. Y.

DIAPHRAGM FOR REGULATORS.

1,361,727.

Specification of Letters Patent. Patented Dec. 7, 1920.

Application filed January 29, 1919. Serial No. 273,904.

To all whom it may concern:

Be it known that I, WILLIAM HODGSON, a citizen of the United States, and a resident of the borough of Bronx, county of Bronx, 5 city and State of New York, have invented certain new and useful Improvements in Diaphragms for Regulators, of which the following is a specification.

My invention relates to elastic resilient 10 metallic diaphragms such as used in the type of regulator set forth in my concurrent application Serial No. 273,905 bearing even date of filing herewith. As therein stated, these diaphragms, for the purpose of 15 attaining a maximum of strength and flexibility combined with sensitiveness and responsiveness to fluctuation in fluid pressure, are made of relatively thin elastic resilient material, preferably copper, and are also 20 preferably corrugated for reinforcement. Hence these diaphragms are somewhat fragile in character and easily distorted or ruptured if subjected to unusual or rough treatment.

25 The object of my present invention is not only to strengthen and safeguard the diaphragm as a whole, but also to adapt it, as a special and separate article of manufacture, for use as a replacement for worn out 30 diaphragms for which it may be readily substituted without the aid of skilled labor. To this end I form my improved diaphragm with a marginal reinforcement which is larger in cross section than the thickness 35 of the diaphragmatic sheet itself, thereby rendering the diaphragm practically rigid peripherally without impairing the elasticity and resilience of the main, medial portion thus framed, as it were, within a rim of sufficient strength to maintain the requisite shape 40 of the diaphragm during packing, transportation and manipulation, if treated with reasonable care.

Furthermore this permanent peripheral 45 reinforcement of the diaphragm not only adapts it for independent transportation

and manipulation as a replacement, but the rim bead, when the diaphragm is incorporated into the structure of the regulator, also further performs the function of the annular gripping member set forth in my said concurrent application for patent, in that it is adapted to fit into the annular seating groove formed in the pressure chamber base plate and to be clamped therein by the cap 55 plate of the regulator; all as hereinafter more fully set forth.

In the accompanying drawings,

Figure 1, is a central vertical sectional elevation of a regulator of the type for 60 which my improved diaphragm is intended, showing its position in and with relation thereto;

Fig. 2, is a face view of the diaphragm; and

Fig. 3, is a sectional detail showing the rim bead formed by wrapping the edge of the diaphragm around an annular cylindrical core;

Fig. 4, is a view like unto Fig. 3, showing 70 a modification in the core wrap of the rim bead;

Fig. 5, is a sectional detail of the rim bead as formed by turning the edge of the diaphragm over upon itself in the shape of 75 a tight spiral;

Fig. 6, is a similar view showing a modification in which the rim bead is formed by folding over the edge of the diaphragm upon itself;

Fig. 7, is a sectional detail showing a hollow rim bead formed by inturning the edge of the diaphragm.

In this type of regulator, as shown in Fig 1, the diaphragm D, is clamped peripherally against the rim b^3 , of the pressure chamber base plate B, by means of a cap plate C,—screw bolts c, and nut c', being used as the securing means. The base plate B, of the fluid pressure chamber b^7 , is 90 formed with the usual threaded nipple b^2 , for engagement with a pipe or other connec-

tion with a source of fluid pressure, which latter enters the said pressure chamber b' , through the inlet passage b^5 , in said nipple b^2 .

5 The plunger P , which transmits the motion derived from the diaphragm D , to the valve or damper actuating lever L , is connected with the latter by a coupling link K ; and said lever passes through the ful-

10 crum link F , and is connected therewith in the usual manner by means of a set screw f . c^4 , is a stop rest on the cover C , for the support of the lever L , and the plunger P , when the diaphragm D , is deflated, as set

15 forth in my aforesaid concurrent application No. 273,905. b^4 , is an annular groove formed in the rim b^3 , of the pressure chamber base plate B , for the seating of the annular peripheral reinforcement bead d , of

20 the diaphragm D ; and c^2 , is a corresponding coincidental capping groove formed in the inner face of the cover C , also for engagement with said peripheral reinforcement bead d , of the diaphragm D . Thus

25 the peripheral reinforcement bead d , of the diaphragm conforms also to the purpose and requirements of a packing and securing ring by means of which the diaphragm is securely held in centralized position within and be-

30 tween the pressure chamber base plate B , and the cover plate C .

It is obvious that the peripheral reinforcement bead d , of the diaphragm D , may be formed in various ways and of various shapes without departing from the spirit and intent of my invention in this respect, the gist of the invention consisting essentially in providing the edge of the diaphragm with a circumscribing rim bead of

35 greater cross section than the thickness of the sheet of metal constituting the body of the diaphragm, which is preferably made of a relatively thin sheet of copper corrugated to attain a maximum of strength, elasticity

40 and resilience for a given size and weight of plate.

Where it is desired to have the peripheral reinforcement bead d , compressible to a high degree, the simple turning over of the edge 50 of the diaphragm D , upon itself, as in Fig. 7, will answer the purpose; or a folding over thereof as in Fig. 6. Where a less compressible marginal reinforcement is required, the edge of the disk D , may be turned over into

55 a tight spiral, as in Fig. 5, or the edge of the disk D , may be upset around an annular core d' , of suitable material, preferably metallic wire, or a wire formed of an alloy adapted to the purpose. Where a relatively

60 soft core d' , is used, as of lead wire, the marginal reinforcement bead d , affords an ideal means for attaining a tight, hermetical seal between said edge of the diaphragm D , and the rim b^3 , of the pressure chamber base

65 plate B .

Thus my marginal reinforcement bead d , of the diaphragm D , not only affords adequate means for securing the latter in place in the regulator casing as above set forth, but it also frames and stiffens the diaphragm 70 to such an extent that, with reasonable care in packing, transportation and manipulation, it may be advantageously manufactured and used as a replacement for old or defective diaphragms, since it combines in 75 a unitary structure both elastic resilient disk and securing and packing rim. Hence, when used as a replacement it is only necessary to remove the bolts and nuts c , c' , from the regulator, raise the cap plate C , remove 80 the old diaphragm and substitute the replacement D , and then again secure the cap plate C , to the pressure chamber base plate B ,—all simple operations not requiring skilled or expert labor.

85

What I claim as my invention and desire to secure by Letters Patent is,

1. As an article of manufacture, an integral replacement diaphragm of the character designated, comprising a corrugated 90 plate of sheet metal formed with a solid peripheral reinforcement rim bead substantially round in cross section and of greater aggregate thickness than the body of the plate, said peripheral reinforcement rim 95 bead also constituting packing and securing means by which the diaphragm may be firmly held in centralized position between the base and cover of a regulator, as set forth.

100

2. As an article of manufacture, a one piece diaphragm of the character designated, comprising a corrugated plate of sheet metal having an integral peripheral reinforcement rim bead essentially round in 105 cross section and formed by upsetting the edge of the plate upon itself, said reinforcement rim bead being of greater aggregate thickness than the body of the sheet and constituting packing and securing means by 110 which the diaphragm may be firmly held in centralized position between the base and cover of a regulator as set forth.

3. As an article of manufacture, a diaphragm of the character designated, comprising a corrugated plate of sheet metal formed with a peripheral reinforcement rim bead essentially round in cross section and of greater aggregate thickness than the body of the plate, said rim bead consisting of an 115 annular core around which the edge of the diaphragm is upset to form conjointly a circumscribing plate frame which also constitutes packing and securing means by which the diaphragm may be firmly held in 120 centralized position between the base and cover of a regulator, as set forth.

125

4. As an article of manufacture, a diaphragm of the character designated, comprising a corrugated plate of sheet metal 130

formed with a peripheral reinforcement rim bead essentially round in cross section and of greater aggregate thickness than the body of the plate, said rim bead consisting of an
5 annular core of lead wire around which the edge of the diaphragm is upset to form conjointly a circumscribing plate frame which also constitutes packing and securing means

by which the diaphragm may be firmly held in centralized position between the base and 10 cover of a regulator, as set forth.

WILLIAM HODGSON.
